ABSTRACT

A word association game wherein the players derive different but commonly known word sets from elements of a previous commonly known set including a die, a board, a plurality of preprinted cards, a "minute glass" timer, a plurality of pads and writing instruments, and game tokens for movement on the board. The board has a path of adjacent spaces, which path is arranged in a FIG. 8 with the start space at the crossing. The spaces are color coded in one of six different colors. The preprinted cards each have a blind side and a face side. The latter has six different color coded areas with a different word set in each. A word set is a common phrase (e.g. TIE CLASP) or single (e.g. BLACKJACK) which includes a plurality of different word elements (e.g. TIE, CLASP, BLACK, JACK). Each card has different word sets from the other cards with those of one color coding being of a different word sets from the other categories: PEOPLE, PLACES, TITLES, THINGS, GENERAL and SPORTS/GAMES. A player's turn includes throwing a die and drawing a card at random. The player's piece is moved the number of spaces on the die to a space whose color code determines the category and thus the starting word set. The player must in a time period enter successive word sets on the score pad, each entry related to the previous word set by using one of its elements for points and/or movement of tokens. Players alternate turns until one reaches a set goal (e.g. 100 points).

5 Claims, 2 Drawing Sheets

Fig. 2

WORD ASSOCIATION GAME

FIELD OF THE INVENTION

This invention relates to a novel word association game for two or more players.

BACKGROUND OF THE INVENTION

Word games provide amusement and education. Many of such games, for example, that disclosed in U.S. Pat. No. 4,854,594 to Eaton, employ a board wherein players move tokens about a board and answer trivia questions related to the space upon which their tokens land. Another game employing trivia questions is disclosed in U.S. Pat. No. 4,884,815 to Glenn, which game also employs decoding a number to letters which are rearranged by the players into words. Others, such as U.S. Pat. No. 4,666,161, Elesie, et al., employ a track or pathway on a board and have players draw cards with words and definitions, and wherein players advance by knowing the correct definition of drawn words. In other word games, such as that shown in U.S. Pat. No. 4,089,527, to Roth, a player advances by memorizing items on cards. Word puzzles are involved in the game of U.S. Pat. No. 4,941,668, to Mobrem, and U.S. Pat. No. 4,911,452 to Marchese requires players to name a series of words which fit within a particular category and start with particular letters. U.S. Pat. No. 4,955,614 to Buda involves guessing particular words by a process of selecting and eliminating letters contained in the word. And U.S. Pat. No. 3,606,336 to Krause is directed to a word association game wherein the player builds words from lettered tiles obeying the rule that successive words start from the last letter of the prior word and have a length derived from chance.

Clever and as educational as these games and others like them may be, there is still room for additional educational and entertaining word games, and especially for one which does not rely on knowledge of definitions, trivia facts, or short time memorization of patterns or items, but instead develops and rewards free association.

SUMMARY OF THE INVENTION

A word association game in accordance with the present invention includes a recorded data base of a plurality of different commonly known word sets (such as TIE CLASP or BLACKJACK), each of which includes a plurality of word elements (such as TIE, CLASP, BLACK, and JACK). Means for randomly selecting one of these word sets (e.g. BLACKJACK) is provided, as well as timing means and means for recording a sequence of word sets, starting from the one which, to count toward winning, must be commonly known, and sets employing one word element (e.g. JACK FROST, FROST BITE, BITE THE BULLET, BULLET TRAIN) from the preceding word set of the sequence. A player (or team) advances relative to his competitors by recording word sets in a sequence in a set period, and thus the game rewards and encourages quick wit and free association of commonly known phrases or word sets.

The invention, together with further advantages and features thereof, may best be understood by reference to the following description taken in connection with the accompanying drawings, in the several figures of which like reference numerals identify like elements.

BRIEF DESCRIPTION OF THE DRAWINGS

FIG. 1 is a plan view of a preferred embodiment of a game board constructed in accordance with the present invention.

FIG. 2 is a perspective view of the equipment (namely, score pads, writing instruments, die, timer, pre-recorded word set cards [two of which are shown on a slightly enlarged scale for clarity], and player tokens), which together with the board of FIG. 1 is the presently preferred best mode of practicing the present invention.

DETAILED DESCRIPTION OF ONE PREFERRED EMBODIMENT

Referring to FIG. 1, there is depicted a board 10 having a plurality of spaces 11-53 arranged in a path or track 8 which is laid out in the general shape of a FIG. 8. Each of the 43 individual spaces has its center color coded in one of six colors: red, green, blue, yellow, orange or purple. The cross-over space 11 serves as the "start" and is so labeled. A player or team of players chooses a token (such as one of the six tokens 61-66 of FIG. 2) which for ease of identification are differentiated from each other by color (different tokens 61-66 being red, blue, orange, green, yellow or purple).

The direction of travel on the path 8 is one-way in the directions of the arrows shown on spaces 12, 32, 33 and 53. The only choice of direction is upon leaving "start" space 11, and that is preferably the choice of the player or team. Once committed, the token travels the FIG. 8 track 8 going by the cross-over space 11 in a straight line from space 53 to space 12 or from space 32 to space 33.

Six of the spaces, i.e. spaces 15, 22, 29, 36, 43 and 50, have indicia on them ("SI") which sets them off from the majority of the spaces 11-53. These spaces have special instructions associated with them, and tokens landing on them requires the player to follow those instructions, which will be explained below under "Rules."

As shown in FIG. 2, there is provided a timer 70 which preferably may be a simple "minute glass." In use, this timer is turned over at the start of a player's (or team's) turn and when the sand has run out so has the turn.

Each player or team is provided with means for recording a sequence of word sets and, as also shown in FIG. 2, this is preferably a score pad 72 and pencil 74.

The game includes a data base of word sets, each commonly-known phase or word set having a plurality of elements. This collection is preferably included in a set of cards 80 which is also shown in FIG. 2. These cards 80 have a back side (the blind side) which, like the back or ordinary playing cards, has the same design on each. (The two cards shown in FIG. 2 with their face side showing are depicted on a slightly enlarged scale for clarity. All such cards are preferably the same size.) The face side of the cards 80 are all laid out in the same arrangement, that is, with six colored border rectangles 81-86. These are colored red (81), orange (82), yellow (83), green (84), blue (85) and purple (86). Inside each rectangle is a different word set 91-96 (or 91'-96'). These word sets are different on each card in the set.

The word sets of the data base of cards 80 are in different groups or classifications or categories which are color-coded. These categories and their colors are PEOPLE—Red

PLACES—Orange

TITLES—Blue

THINGS—Yellow

GENERAL—Green

SPORTS/GAMES—Purple

For convenience of the players, the names of these categories with their associated colors as a background are placed on the board 10 (FIG. 1) at 99. These colors are, of course, the same as those used on the central areas of the spaces 11-53. That is, the centers of the spaces 11, 17, 25, 29, 34, 42, 44 and 52 are purple—the SPORTS/GAMES color. And the centers of the spaces 12, 20, 22, 28, 30, 38 and 46 are orange—or the PLACES color, while the center areas of spaces 13, 21,

48 are green—the GENERAL category color coded. Completing the list, the center areas of spaces 15, 19, 27, 35, 37, 45 and 53 are red, for PEOPLE, and the remaining spaces 17, 25, 33, 41, 49 and 51, are, for TITLES,

5 color-coded blue in their centers. Note that of the 43 spaces eight are purple and seven are of each of the other colors. This provides a more or less equal chance for a token to land on each color and thus a more or less equal chance to select each category during the course of a game.

As mentioned above, the cards 80 have six color coded word sets each, one of each of the six categories. Examples of these are set out below in Table 1 for a number of different cards listed from categories.

TABLE 1

PEOPLE	PLACES	THINGS	GENERAL	TITLES	SPORTS/GAMES
David Letterman	Shepherd of the Hills Farms	Cover Letter	Sunny Side Up	Fantasy Island	Speed Rating
Eric The Red	Ripley, Tennessee	Drill Press	Shipshape	Great Pretender	Second Base
Julius Caesar	Longwood Gardens	Juice Glass	Leave No Stone Unturned	Newsweek	Montreal Canadians
Robin Hood	Dead Sea	Scaletail	Coyote	The House of the Seven Gables	Down Rigger
Tony Bennett	Battle Creek, Michigan	Universal Joint	Ugly	Against the Grain	Bank Shot

23, 31, 39, 47 and 50 are yellow—the THINGS color

Tables 2 through 6 are of more examples:

	Fort Lauderdale, Florida				

Also shown in FIG. 2 is a single die 100 which with the cards 80 and board 10 serves as means for randomly selecting one of the included word sets such as those listed above in Tables 1, 2, 3, 4, 5 and 6, as will be explained below.

RULES

A set of rules is also provided with the game, which rules may read as follows:

Rules for Basic Play

Equipment:

COMBONOTIONS contains one game board, one die, one minute timer, six player tokens, six score pads, six pencils and 798 word combo cards.

Object of the Game:

To be the first team (consisting of one or more players) to reach 100 points by creating various word combinations based on the previous word combination. (These combinations will be described later in detail.)

Preparation:

Place the timer die, and combo cards, so that all players have access to them. Divide the players into equal teams. Each team should be issued a token, a scorecard, and a pencil. Place a token for each team on the starting space located in the center of the board. Select a member from each team to roll the die to determine which team rolls first. The highest roller begins. Each team should select a person to write the combinations down. (Note: the scribe may change between team members for each round.)

Play:

Roll the die. Following either arrow, move the token the appropriate number of spaces. When the token lands on a colored square, a card is drawn from the card box. The color of the square's center determines the cate-

gory of the initial word combo. The six categories are PEOPLE, PLACES, TITLES, THINGS, GENERAL, and SPORTS/GAMES. The scribe announces the initial word combo. He should be given sufficient time to write down the initial word combo in the space provided on the score pad before the opposing team starts the timer. Once the timer is started, the scribe and his teammates being creating new word combinations by using one or more words from the previous combo until the timer has run out. The word combos created must be well known people, places, things, titles, sports/games or phrases. The last word combo created becomes the starting point for the next word combo to be created. Please see example 1a, 1b and 1c. NOTE: The first word combo created does not necessarily have to be in the same category as the initial word combo.

Scoring

At the end of each round, the scribe totals up the points with one point awarded for each valid word combination (including the initial word combo written by the scribe. If time expires while a word combo is being written, the team receives full credit for that combo. Play continues until one team reaches at least 100 points.

Special Instruction (S.I.) Spaces:

When a team's token lands on a S.I. space, roll the die an extra time to determine which of the following special instructions apply.

DIE ROLL	SPECIAL INSTRUCTION
1 or 2	SI 1. The word combo created must end with the first word from the previous combo. Please see example 2a.
3 or 4	SI 2. The word combo created must begin with the last word from the previous combo.

-continued

DIE ROLL	SPECIAL INSTRUCTION
5	Please see example 2b.
6	SI 3. No special instructions apply. SI 4. Team loses turn.

Restrictions:

During a round, NO more than 3 combinations can use the same word. This is necessary to eliminate people from using lists. Please see example 3a.

The created word combination must be "well known." By "well known" we mean the word combination has to be an actual or real person, place, title, phrase or thing known to a majority of the players. For example, the word combo "CHICKEN ICE CREAM" would be invalid, because to the best of our knowledge, no such thing exists. From time to time, due to the nature of this game, questionable word combos will occur. The final determination of whether or not a word combo or phrase is valid must ultimately be made by the players.

When creating new combos, variations, portions, or homonyms of a previous word can be used as the starting point of the next word combo. If the starting combo was DOWN COAT, the word "DOWN" could be used to create a multitude of combinations. Examples of the would be "Down By the Old Mill Stream," "Downy Fabric Softener," "Down's Syndrome," "Churchill Downs," etc.

If the created word combo consists of only one word, that word must be able to be phonetically broken apart into at least two smaller words. For example, "LEADERSHIP" can be broken into LEADER and SHIP. Whereas "MISSION" cannot be phonetically broken into two meaningful words; thus, MISSION is an invalid word combo.

Articles of the English language (a, an, the) cannot be used as the basis for creating new word combos. For example, "The Godfather" could not be created from "The Man from Uncle".

Challenging:

At the end of each round, opposing team may challenge the other team's word combos on the basis that the combo falls to meet the above restrictions. If the challenged combo is found invalid, the team only receives points for those combos created before the invalid combo. However, if the challenged word combo is valid, the points awarded are doubled for it and each succeeding combo.

Helpful Hints:

If during play a team generates a "dead end combo" (that is, a word combo from which no other combos can be derived), the dead end combo may be erased, making the previous combo the point from which to continue. Also, the scribe should not be overly concerned with spelling or punctuation when writing down combos. He should try to get as many combos written down as

possible. Ditto marks (") may be used if desired to mark similar parts of combos.

Rules for Advanced Play

5 General:

Rules for the advanced game are similar to those of the basic game, with the following changes:

Play:

- After a token lands on any space other than a Special Instruction space, draw a card from each card box. The first card drawn contains the starting word combo; its category is determined by the color of the square's center. The color of the square's border determines the category of the ending word combo from the second card. If the beginning and ending combos have a common word, the ending combo must be redrawn. Once the timer is starting, the scribe and his teammates must attempt to derive the ending word combo from the starting word combo. Please see examples 4a, 4b and 4c.
- 10 The round continues until the ending combo has been derived or time has expired.

Scoring:

- Five points are awarded for reaching the concluding combination. Additional Bonus Points are awarded as follows:

	# of combos used (not including starting or ending combos)	Bonus Points Awarded	Examples
30	1	9	
	2	8	
	3	7	4a
	4	6	
	5	5	
	6	4	4b
	7	3	
	8	2	
	9	1	
	10 or more	No bonus points	4c

Special Instructions (S.I.) Spaces:

When a team's token lands on a S.I. space, before drawing the combo cards, roll the die again. A die roll of 1-3; the rolling team determines categories of the starting and ending word combos. A die roll of 4-6; the opposing team to the left of the rolling team chooses the categories for the starting and ending combinations.

Challenging:

- If an opposing team successfully challenges a word combo, no points are awarded to the rolling team. If an opposing team unsuccessfully challenges a word combo, the points awarded to the rolling team are doubled.

Helpful Hints:

- If the players determine that the one minute time limit is too severe a restriction for the advanced game, the time limit may be extended in one minute intervals by flipping the timer over. All players must agree on the length of time permitted during the rounds.

Examples:

1a CLOWN FACE	1b JOHN WAYNE	1c CHICAGO CUBS
Face the Music	Wayne Newton	Cub Scout
Music Man	Fig Newton	Eagle Scout
Man from Uncle	Fig Tree	Jeep Eagle
Uncle Toms Cabin	Peach Tree	Jeepers Creepers
Cabin Fever	Peaches & Cream	where'd you get
Scarlet Fever	Creamed Corn	those peepers
Scarlet O'Hara	Corn on the Cob	Mr. Peepers
etc.	Ty Cobb	Mister Rogers

-continued

Examples:

		etc.	Roger Rabbit Braer Rabbit etc.
2a TABLESPOON End Table Rear End Step to the Rear Texas Two Step etc.	2c PET ROCK Rock Hudson Hudson Bay Bay Leaf etc.	3a KANSAS CITY, Missouri Kansas State University Indiana University University of Kansas Kansas City Chiefs-INVALID Kansas City Royals-INVALID	
4a FIELD GOAL Soccer Goal Soccer Ball Gum Ball Bubble Gum	4b COFFEE MUG Cup of Coffee Tea Cup Tea Bag Paper Bag Paper Boy Delivery Boy Delivery Room	4c BOOK SHELF School Books School Bell Bell Tower Bell Pepper Salt & Pepper Salt Block Wood Blocks Wood Shop	

It should be clear from the above rules as to the manner of play. However, the purposes of illustrations, let us go through a series of moves in a typical match. For simplicity, let's have only two players (or teams). Although the game would go substantially in the same way, it is easier to describe a two-player match and just as illustrative. Let us assume Red is the first player and the second player is Yellow and that they respectively chose red token 61 and yellow token 63. The die 100 is cast by each and Red wins the right to start. Red places token 61 on space 11 and again throws the die 100 and gets a 6. At this point, he can choose to move his token six spaces in either of two directions (as indicated by the arrows in spaces 12 and 33) and place it on space 17 (blue) or space 38 (orange). Since Red likes the category "Titles" (blue) better than "Places" he chooses to place his token on space 17. Red then (blindly without looking at the faces) draws the card 80 which, let's say, reads:

SONNY LISTON CEDAR POINT, KANSAS SPEEDSTICK BLOW HOT AND COLD THE SHAKIEST GUN IN THE WEST CHIP SHOT

Since he has landed on a blue space, his starting word set is "The Shakiest Gun in the West" and Red writes this down on the top sheet of a pad 72 using a pencil 74. At the same time, Yellow turns over the timer 70. Red enters the following sequence before his turn runs out.

1. The Shakiest Gun in the West
  2. West Virginia
  3. Virginia Ham
  4. Ham and Eggs
  5. The Chicken or the Egg
  6. Chicken Little
  7. Little Richard
  8. Richard Kinney
  9. Kinney Shoes
  10. Shoe Fly Shoe
  11. Fly the Friendly Skies
  12. Officer Friendly
- and thus Red gets 12 points.

(Yellow could "challenge" Red on his 8th entry on the grounds that Richard Kinney is not a commonly known word set, but believing patent lawyers are perhaps famous and Yellow being somewhat cowardly, decides not to risk a challenge.) Yellow places his yellow token at start (space 11) and throws a "1" with die 100. His choices are spaces 12 or 33 and he selects the orange space 12. Picking a card blindly, Yellow gets the following card

---

FRANKLIN D. ROOSEVELT
POWDER RIVER, WYOMING
ENGLISH MUFFIN
ROCK-N-ROLL
HITCHHIKER'S GUIDE TO THE GALAXY
RUNNING BACK

And Yellow enters the following on his pad 72 while the sands run out of the timer 70 which was reset by Red:

1. Powder River, Wyoming
  2. Yellow River, China
  3. John River
  4. Peter River
  5. Mary River
- However, Red being naturally aggressive challenges John River, Peter River and Mary River, citing the restrictions against non-well-known people and repeating the same elements. Yellow gets two points.

Next, Red throws the die 100 again and gets a "5" and thus lands on space 22 which is both orange color-coded and an special rule instruction (SI) space. Following the rules, Red throws the die again and gets a "2". This means that his entered word sets must all end with the first word element of the preceding set. He draws a new card from the pile of cards 80 and its orange-bordered word set reads

SEVEN SISTERS FALLS, MANITOBA
Red enters that and the following on his pad
MAGNIFICENT SEVEN
TRULY MAGNIFICENT
YOURS TRULY
SINCERELY YOURS
MOST SINCERELY
to gain six more pints or a total of 18.

Yellow and Red continue taking turns in this manner until Red wins with 101 points to Yellow's 36.

It should now be apparent that a new and improved word association game has been described and depicted which can be used to develop verbal skills and provided entertainment. While the game has been described in its presently preferred form, many other forms can be employed, for example, it can be adapted to be a computer

game or other timer and random selection means can be employed.

While one particular embodiment of the invention has been shown and described, it will be obvious to those skilled in the art that changes and modifications may be made without departing from the invention and, therefore, the aim in the appended claims is to cover all such changes and modifications as fall within the true spirit and scope of the invention.

We claim:

1. A method of playing a word association game, consisting of a game board defining a FIG. 8 shaped track having a plurality of color coded spaces with a labeled starting space at the center of the board, game pieces, a die, a resetable timer, score pads, writing instruments, a deck of cards with color coded word sets having words, comprising the steps of:

selecting a game piece;

rolling a die;

moving said game piece from the center starting space along the track a number of spaces corresponding to the die roll;

selecting a card from said deck of cards;

selecting a color coded word set corresponding to the color coded space onto which the game piece was moved;

recording said word set onto a score pad;

starting said timer;

creating and recording a sequence of word sets using one or more word elements from a preceding word set until the timer runs out; and scoring the word sets created and recorded during a turn.

5 2. The method of playing a word association game of claim 1, further comprising the step of recording the credit toward winning for the number of created and recorded word sets in the sequence.

10 3. The method of playing a word association game of claim 2, wherein said color coded spaces define different categories by having all of the word sets of each category associated with a different color coding.

15 4. The method of playing a word association game of claim 3, wherein a created and recorded word set is scored only if the word set is commonly known to a majority of players.

20 5. The method of playing a word association game of claim 4, wherein a created and recorded word set is not scored if the word set is repetitive of any preceding word set.
